UNITED STATES PATENT OFFICE

2,227,812

APPARATUS FOR COMPRESSING AIR

Jay Retsema, Muskegon Heights, Mich., assignor
to John Wood Manufacturing Company, Inc.,
Conshohocken, Pa., a corporation of Delaware

Application July 10, 1940, Serial No. 344,681

7 Claims. (Cl. 230—4)

My invention is an improvement over that shown in Letters Patent of the United States No. 1,659,290 granted February 14, 1928, to George W. Gille for Apparatus for compressing air.

5 My invention includes the various novel features of construction, arrangement and method of operation herein disclosed.

In said drawings: Fig. I is an end elevation of an apparatus conveniently embodying my invention.

10 Fig. II is an end elevation of the valve casing shown in Fig. I as seen from the opposite end thereof.

15 Fig. III is a longitudinal sectional view of said valve casing taken on the line III, III in Figs. I and II.

20 Referring to Fig. I my invention is adapted to be used in conjunction with an air compressor, indicated by the dotted circle 1, and of any conventional and well-known design, provided with an after cooler, condenser, outlet conduit 2 connected to the check valve 6 which is connected by the conduit 7 with the air storage tank 8. The check valve 6 conveniently is illustrated as of the construction shown in Letters Patent of the United States No. 2,192,258 granted March 5, 1940, to Chandler, but it is to be understood that a check valve of any conventional type may be used.

25 Said conduit 7 has the upwardly extending branch 7' connected to and supporting the pressure controlled switch mechanism in the housing 4, including a switch of a conventional diaphragm type, such as shown in said Gille or Chandler patents. Said switch mechanism in the housing 4, being subjected to the pressure in the tank 8 through the conduits 7 and 7', opens and closes the circuit to an electric motor which operates the air compressor 1 when predetermined pressures are reached in the tank 8.

30 Said check valve 6 has the bleeder conduit 5 in continual communication with the outlet conduit 2 of the compressor 1. As shown in said 35 Gille patent, the switch mechanism within the housing 4 includes means whereby closure of the motor circuit contemporaneously closes a valve to prevent communication between the bleeder conduit 5 and the condensate drain outlet conduit 3 connected to the valve casing 12; and opening of the motor circuit contemporaneously opens that switch controlled valve to establish communication between the conduits 5 and 3.

35 The tank 8 is conveniently provided with a plurality of supporting legs 9 resting upon the

supporting surface 10 and has the dispensing outlet connection 11, located in any convenient place.

The valve casing 12 is conveniently provided with the solid supporting bar 13, the outer end 5 of which, as shown in Figs. II and III, is screwed into a cross fitting in said conduit 7, to support said casing 12. The single valve casing 12 includes three chambers, comprising; first, the diaphragm chamber 15 having a fluid inlet 16 for 10 condensate and air; second, the valve chamber 17 having the fluid inlet 18 for condensate and air; third, the condensate discharge chamber 19 having the continually open condensate exhaust outlet 20. The condensate drain outlet conduit 15 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680

Casing 12 includes two fluid ports, viz., first, the port 26 from the diaphragm chamber 15 to the condensate discharge chamber 19 and, second, the port 27 extending from the valve chamber 17 to the condensate discharge chamber 19. 35 The effective area of said first port 26 may be variably limited by the needle valve 29 which is open and normally stationary but adjustable in the screw threaded bearing 30 in said casing 12. I have found it convenient to provide said valve 29 with the screw-driver slot 31 at its outer end, by which its axial adjustment may be effected, and as indicated in Fig. II, I provide the set screw 32 in threaded engagement with the casing 12 to 40 impinge upon the smooth cylindrical portion 33 of valve 29 in the bearing 30, to hold the valve in adjusted position.

I provide the valve seat 35 in valve chamber 17 around port 27, for the poppet valve 36 which has 50 the stem 37 extending through port 27 in co-operative relation to the diaphragm 24. Poppet valve 36 is continually stressed toward its closed position shown in Fig. III by spring 38 which is conveniently supported at its outer end in the 55

screw plug 39 which forms a closure for the outer end of the valve chamber 17, and is seated upon the gasket 40.

Said diaphragm 24 is conveniently formed of 5 rubber and reinforced at its axis by the plane metal disk 41 held in place by the axial stud 42 which extends through said disk and through the concavo-convex disk 43 which is continually stressed toward the diaphragm 24 by the spring 10 45 encircling said stud and abutting against the washer 46 on said stud; said washer being held in place by the cotter pin 47.

The construction and arrangement above described are such that when the air compressor 15 pump ceases its operation due to opening of the motor switch, condensate and compressed air from the after cooler outlet pipe 2, passes through the conduits 5 and 3 and inlet 16 to the diaphragm chamber 15, and discharges the condensate from the after cooler through the port 26 into the condensate exhaust chamber 19 and out through its exhaust outlet 28. Simultaneously, such influx of condensate and air to the diaphragm chamber 15 flexes the diaphragm 24 against the 20 25 left hand end of the stem 37 of the poppet valve 36 unseats the latter against the stress of its spring and permits influx of condensate from the bottom of the tank through the conduit 22 and inlet 18 of the valve chamber 17, under the air 30 35 pressure in the tank, and into the condensate exhaust chamber 19 through the port 27 and out through said exhaust outlet 28; whereby, all of the condensate formed in the apparatus by compression of air, is automatically ejected therefrom, through the single exhaust outlet 20 in the valve casing 12, and by but a small quantity of the air compressed.

However, the apparatus may be otherwise constructed, arranged and controlled without departing from the essential features of my invention as defined in the appended claims.

I claim:

1. In apparatus for compressing air; the combination with an air compressor pump having an atmospheric air inlet and a compressed air outlet; of a condenser connected to said outlet; a compressed air storage tank; an air conduit connecting said condenser to said tank; a check valve in said conduit; a single casing, enclosing three chambers, comprising; first, a diaphragm chamber, having a fluid inlet, for condensate and air; second, a valve chamber having a fluid inlet for condensate and air; third, a condensate discharge chamber, having a continually open condensate 45 50 55 60 65 70 75 exhaust outlet; a drain outlet conduit for condensate from the compressor and condenser, connected to the diaphragm chamber inlet; a drain outlet conduit for condensate from the bottom of the storage tank, connected to the valve chamber inlet; a flexible diaphragm separating the diaphragm chamber from the condensate discharge chamber; a first fluid port from the diaphragm chamber to the condensate discharge chamber; an open, normally stationary, but axially adjustable valve for variably limiting the effective area of said first port; a second fluid port from the valve chamber to the condensate exhaust chamber; a valve seat in said valve chamber around said second port; an automatically operative poppet valve, in the valve chamber and fitted to said seat, having a stem extending through said second port in cooperative relation to the diaphragm; and a spring continually stressing said poppet valve toward its seat to close the second port; whereby influx of condensate and air from the compressor through the inlet to the diaphragm chamber, discharges condensate from the compressor through the first port into the condensate exhaust chamber and out through its exhaust outlet, and, simultaneously, flexes the diaphragm to unseat the poppet valve, against the stress of its spring, and permits influx of condensate from the tank, under the air pressure in the tank, and into the condensate exhaust chamber and out through its exhaust outlet; whereby, all of the condensate formed in the apparatus by compression of air, is automatically ejected therefrom, through the single exhaust outlet in the single casing, and by a small quantity of the air compressed.

the compressor and condenser through the inlet to the diaphragm chamber, discharges condensate from them through the first port into the condensate exhaust chamber and out through its exhaust outlet, and, simultaneously, flexes the diaphragm to unseat the poppet valve, against the stress of its spring, and permits influx of condensate from the tank, under the air pressure in the tank, and into the condensate exhaust chamber and out through its exhaust outlet; whereby, all of the condensate formed in the apparatus by compression of air, is automatically ejected therefrom, through the single exhaust outlet in the single casing, and by a small quantity of the air compressed.

2. In apparatus for compressing air; the combination with an air compressor having an atmospheric air inlet and a compressed air outlet; of a compressed air storage tank connected to said outlet; a single casing, enclosing three chambers, comprising; first, a diaphragm chamber, having a fluid inlet, for condensate and air; second, a valve chamber having a fluid inlet for condensate and air; third, a condensate discharge chamber having a continually open condensate exhaust outlet; a drain outlet conduit for condensate from the compressor, connected to the diaphragm chamber inlet; a drain outlet conduit for condensate from the bottom of the storage tank, connected to the valve chamber inlet; a flexible diaphragm separating the diaphragm chamber from the condensate discharge chamber; a first fluid port from the diaphragm chamber to the condensate discharge chamber; an open, normally stationary, but adjustable valve for variably limiting the effective area of said first port; a second fluid port from the valve chamber to the condensate exhaust chamber; a valve seat in said valve chamber around said second port; an automatically operative poppet valve, in the valve chamber and fitted to said seat, having a stem extending through the second port in cooperative relation to the diaphragm; and a spring continually stressing said poppet valve toward its seat to close the second port; whereby influx of condensate and air from the compressor through the inlet to the diaphragm chamber, discharges condensate from the compressor through the first port into the condensate exhaust chamber and out through its exhaust outlet, and, simultaneously, flexes the diaphragm to unseat the poppet valve, against the stress of its spring, and permits influx of condensate from the tank, under the air pressure in the tank, and into the condensate exhaust chamber and out through its exhaust outlet; whereby, all of the condensate formed in the apparatus by compression of air, is automatically ejected therefrom, through the single exhaust outlet in the single casing, and by a small quantity of the air compressed.

3. In apparatus for compressing air; the combination with an air compressor having an atmospheric air inlet and a compressed air outlet; of a compressed air storage tank connected to said outlet; a single casing, enclosing three chambers, comprising; first, a diaphragm chamber, having a fluid inlet, for condensate and air; second, a valve chamber having a fluid inlet for condensate and air; third, a condensate discharge chamber having a continually open condensate exhaust outlet; a condensate drain outlet conduit from the compressor, connected to the diaphragm chamber inlet; a condensate drain outlet conduit from the bottom of the storage tank, connected to the valve chamber inlet; a flexible diaphragm

separating the diaphragm chamber from the condensate discharge chamber; a first fluid port from the diaphragm chamber to the condensate discharge chamber; means for variably limiting the effective area of said first port; a second fluid port from the valve chamber to the condensate exhaust chamber; an automatically operative poppet valve, in the valve chamber, having actuating means extending through the second port 5 in cooperative relation to the diaphragm; and a spring continually stressing said poppet valve to close the second port; whereby influx of condensate and air from the compressor through the inlet to the diaphragm chamber, discharges condensate from the compressor through the first port into the condensate exhaust chamber and out through its exhaust outlet, and, simultaneously, flexes the diaphragm to unseat the poppet valve, and permits influx of condensate from the tank, under the air pressure in the tank, and into the condensate exhaust chamber and out through its exhaust outlet; whereby, all of the condensate formed in the apparatus by compression of air, is automatically ejected therefrom, through the single exhaust outlet in the single casing, and by a small quantity of the air compressed.

4. In apparatus for compressing air; the combination with an air compressor having an atmospheric air inlet and a compressed air outlet; of a compressed air storage tank connected to said outlet; a single casing, enclosing three chambers, comprising; first, a diaphragm chamber, having a fluid inlet, for condensate and air; second, a valve chamber having a fluid inlet for condensate and air; third, a condensate discharge chamber having a continually open condensate exhaust outlet; a condensate drain outlet conduit from the compressor, connected to the diaphragm chamber inlet; a condensate drain outlet conduit 10 from the bottom of the storage tank, connected to the valve chamber inlet; a flexible diaphragm separating the diaphragm chamber from the condensate discharge chamber; a first fluid port from the diaphragm chamber to the condensate discharge chamber; a second fluid port from the valve chamber to the condensate exhaust chamber; an automatically operative poppet valve, in the valve chamber, having actuating means extending through the second port in cooperative 15 relation to the diaphragm; and a spring continually stressing said poppet valve to close the second port; whereby influx of condensate and air from the compressor through the inlet to the diaphragm chamber, discharges condensate from the compressor through the first port into the condensate exhaust chamber and out through its exhaust outlet, and, simultaneously, flexes the diaphragm to unseat the poppet valve, and permits influx of condensate from the tank, under 20 the air pressure in the tank, and into the condensate exhaust chamber and out through its exhaust outlet; whereby, all of the condensate

formed in the apparatus by compression of air, is automatically ejected therefrom, through the single exhaust outlet in the single casing, and by a small quantity of the air compressed.

5. In apparatus for compressing air; a casing, 5 enclosing three chambers, comprising, first, a diaphragm chamber, having a fluid inlet, for condensate and air; second, a valve chamber having a fluid inlet for condensate and air; third, a condensate discharge chamber, having a continually 10 open condensate exhaust outlet; a flexible diaphragm separating the diaphragm chamber from the condensate discharge chamber; a first fluid port from the diaphragm chamber to the condensate discharge chamber; an open, normally 15 stationary, but axially adjustable needle valve for variably limiting the effective area of said first port; a second fluid port from the valve chamber to the condensate exhaust chamber; a valve seat in said valve chamber around said second port; 20 an automatically operative poppet valve, in the valve chamber and fitted to said seat, having a stem extending through the second port in cooperative relation to the diaphragm; and a spring continually stressing said poppet valve toward 25 its seat to close the second port.

6. In apparatus for compressing air; a casing, enclosing three chambers, comprising, first, a diaphragm chamber, having a fluid inlet; second, a valve chamber, having a fluid inlet; third, a condensate discharge chamber, having a condensate exhaust outlet; a pressure responsive diaphragm separating the diaphragm chamber from the condensate discharge chamber; a fluid port between 30 said first and third chambers; a valve variably determining the effective area of that port; a fluid port between said second and third chambers; an automatically operative, pressure responsive, valve controlling the latter port; means operatively relating the diaphragm to the latter 35 valve, for opening it by fluid pressure in the diaphragm chamber; and a spring opposed to the diaphragm pressure, to close the latter valve.

7. In apparatus for compressing air; a casing, enclosing three chambers, comprising, first, a 45 pressure responsive means chamber, having a fluid inlet; second, a valve chamber, having a fluid inlet; third, a condensate discharge chamber, having a condensate exhaust outlet; pressure responsive means in the pressure responsive 50 chamber; a fluid port between said first and third chambers; a valve variably determining the effective area of that port; a fluid port between said valve chamber and said condensate discharge chamber; an automatically operative, pressure responsive, valve controlling the latter port; means operatively relating the pressure responsive 55 means to the latter valve, for opening it by fluid pressure in the pressure responsive chamber; and a spring opposed to the pressure of the pressure 60 responsive means to close the latter valve.

JAY RETSEMA.
